By J. M. Doremus
Attorney

UNITED STATES PATENT OFFICE.

JAMES ALEXANDER GREIG, OF WILLOWIE, SOUTH AUSTRALIA.

BICYCLE.

SPECIFICATION forming part of Letters Patent No. 636,038, dated October 31, 1899.

Application filed November 8, 1898. Serial No. 695,863. (No model.)

To all whom it may concern:

Be it known that I, JAMES ALEXANDER GREIG, pastoralist, a subject of the Queen of Great Britain, residing at Willowie, in the 5 Colony of South Australia, have invented certain new and useful Improvements in Bicycles and other Velocipedes, of which the following is a specification.

My invention relates to the construction of 10 the frames of bicycles and other velocipedes, and more particularly to those driven by chain gearing.

The object of my invention is to provide a 15 construction of the rear portion of the frame which will permit of the back wheel being easily and expeditiously removed and replaced. By this means the sprocket-wheel attached to the back wheel can be quickly 20 changed and the gear raised or lowered, as required. I accomplish this object (a) by constructing the rear portion of the frame with a hinged piece forming the lower part of the slot in which the axle of the rear wheel is attached and (b) by providing a spring-catch 25 by which the sprocket-wheel is retained in place.

Referring to the accompanying drawings, in which my invention is shown as applied to 30 an ordinary rear-driving bicycle, Figure 1 is a side view of the back portion of the machine, showing the hinged portion of the frame. Fig. 2 is an end view of the clamp and thumb-screw for securing the hinged portion of the frame; and Fig. 3, a section through line *a b*, 35 Fig. 1, showing the pivot-bolt of the hinged portion of the frame.

Similar letters of reference indicate corresponding parts throughout the drawings.

A A are the arms of the fork of the rear 40 portion of the framework, formed in the ordinary way of steel tubing, for the reception of the back wheel.

My invention is described with reference to 45 one side only, it being understood that the two are alike.

The arm A, instead of being provided with a slot at its outer side, in the ordinary way, for the reception of the axle of the back wheel, is constructed in two parts A' and A². The 50 upper part A' is provided toward the rear with a slot A³. The lower part or jaw-piece A² is

hinged upon the upper part A' by a screw-bolt H, passing through the slot A³. This screw-bolt H is of special construction, as shown in Fig. 4, in order to prevent it moving 55 along in the slot A³, and at the same time providing a free pivot for the hinged piece A². For this purpose the bolt H is provided, in addition to the head H', with a shoulder H², which passes through a hole of corresponding 60 size in the jaw-piece A². As the nut H³ is screwed up this shoulder H² bears against the outer side of the upper part A', and the bolt H is thus held rigidly in position in the slot A³, while allowing the jaw-piece A² to 65 move freely thereon. By this means the jaw-piece A² can be adjusted in the slot A³ in order to tighten the chain when required. To the rear end of the jaw-piece A² is pivoted a clamp B, provided with a thumb-screw B', by 70 means of which the two parts A' A² are securely held together.

The upper edge of the jaw-piece A² is provided with a series of notches C, adapted to receive one end of the spindle E of the back 75 wheel. The jaw-piece A² may be provided with any number of notches C, according to the desired number of variations in the gear. The notches C serve the purpose of allowing the back wheel to be moved forward or back- 80 ward, according to the size of sprocket-wheel D employed, in order to give the necessary tension to the chain.

For the purpose of altering the gear the rear sprocket-wheel D is screwed onto the 85 hub G' in the ordinary way; but instead of the usual lock-nut I provide an improved spring-catch for retaining it in position. This spring-catch consists of a small bar F, passing through the flanges G' of the hub G of 90 the back wheel and a hole D' in the sprocket-wheel D and is actuated and held in place by a spring F'.

When it is desired to change the gear of the machine, the thumb-screws B' upon each 95 side are loosened and the clamp B unfastened. This allows the jaw-piece A² to drop, and the chain being slipped over the sprocket the back wheel is easily and expeditiously removed from the frame. The spring catch-piece F is then pulled back and the sprocket-wheel D removed. This is now replaced by 100

a fresh sprocket-wheel having a larger or smaller number of teeth, the spring catch-piece F engaging with a hole made therein for the purpose. The back wheel is then re-
5 placed in the frame, the ends of the spindle E being placed in the notches in the jaw-piece A² on each side, so that if the sprocket-wheel has a smaller number of teeth than the previous one the spindle is placed in the
10 notches to the rear, while if it possesses a larger number of teeth it is placed in notches to the front, thus giving the necessary tension to
15 the chain. The jaw-piece is then fixed in position by means of the clamps B and thumb-screws B', and the machine is again ready for use.

Having now particularly described and ascertained the nature of my said invention and in what manner the same is to be performed,
20 I declare that what I claim is—

1. In a bicycle or other velocipede, the arm of the fork of the rear portion of the framework made in two parts, a fixed and a movable part, the fixed part provided with an
25 elongated slot and the movable part provided with a series of recesses on its upper edge each notch adapted to receive the spindle of the back wheel of the vehicle, a screw-bolt by which one end of the movable part of said

arm is hinged in the slot of the fixed part of 30 said arm and rendered adjustable in said slot, and means for locking the free end of the movable part to the fixed part.

2. In a bicycle or the like, arm A of the frame having a two-part end, part A' rigid 35 with A, and A² pivoted thereto, said pivoted part A² having notches C with curved bottoms on its upper edge adapted to directly receive a spindle, means for securing the outer end of part A² to part A' and for releasing 40 the same.

3. In a bicycle or the like, arm A of the frame having a two-part end, part A' rigid with A, and A² pivoted thereto, by means of an elongated slot in part A' and a pivot there- 45 in having means to secure it at any desired position in said slot said pivoted part A² having notches C with curved bottoms on its upper edge adapted to directly receive a spindle, means for securing the outer end of part 50 A² to part A' and for releasing the same.

In testimony whereof I have hereunto set my hand in presence of two subscribing witnesses.

JAMES ALEXANDER GREIG.
